UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

PILOT BEAM.

Application filed August 8, 1922. Serial No. 580,396.

To all whom it may concern:

Be it known that I, CHARLES T. WESTLAKE, a citizen of the United States, residing at St. Louis, Missouri, have invented a certain 5 new and useful Improvement in Pilot Beams, of which the following is a full, clear, and exact description, such as will enable others skilled in the art to which it appertains to make and use the same, reference being had to the accompanying drawings, forming part of this application.

My invention relates to pilot beams for locomotives and consists in a beam preferably formed of a one-piece casting and 15 adapted to have secured thereto extraneous members such as a pilot, pilot braces, signal brackets, front end braces, and a drawbar pocket.

One object of my invention is to so construct 20 such a beam that adequate strength and stiffness is provided where these various parts are secured. This preferably results in a beam of one or more box-like cross sections.

25 It is usual in pilot beam construction to extend the bolts, which secure such members to the beam, clear through the beam. Such practice, of course, necessitates a bolt as long as the width or depth of the beam, and 30 another object of my invention is to construct a beam so that short bolts only extending through the wall of the beam to which the extraneous member is secured may be used.

35 In the accompanying drawings which illustrate a selected embodiment of my invention—

Figure 1 is a front view of my improved pilot beam.

40 Figures 2 and 3 are horizontal sections taken on lines 2—2 and 3—3, respectively, of Figure 1.

Figure 4 is a vertical transverse section taken substantially on line 4—4 of Figure 1 45 and illustrating the application of different equipment to the beam.

The beam comprises a top wall 1, a bottom wall 2, a front wall 3, a rear wall 4, and 50 an intermediate horizontal wall 5. Top wall 1 and intermediate wall 5 extend from end to end of the beam as do the upper portions of front and rear walls 3 and 4. The bottom wall 2 terminates a substantial distance from the ends of the beam and the middle 55 portion of the bottom wall is depressed at 6

to provide adequate backing for a drawbar pocket A.

To lighten the construction and to provide access to the interior faces of the walls of the beam, the ends of the latter are left open. 60 In making beams of this type it is customary to use metal rods to secure cores, which metal rods have to be removed after the casting of the beam, and for this reason also it is desirable that the beam be open at the 65 end so that there will be an uninterrupted passageway for removal of the bars and the cores. Integral push pole pockets 8 are formed on the ends of the beam. Adjacent the ends of the top wall of the beam, holes 70 9 are provided for bolts or rivets which receive the signal flag brackets. Further spaced from the ends of the beams are holes 10 in the top wall of the beam for bolts which attach the front end braces B. 75

In the front wall of the beam above and below intermediate member 5 are holes 11 for bolts which attach the pilot C. Similar holes 12 nearer the center of the beam are provided for receiving bolts which attach 80 the drawbar pocket A. Holes 13 are provided in the bottom wall 2 at the ends thereof for receiving bolts which attach the pilot knee D. Holes 14 in the rear wall 4 of the beam are provided for rivets which secure 85 the beam to the locomotive frame.

I show each of the above-mentioned holes surrounded by a suitable boss formed on the interior of the corresponding beam wall and serving to reinforce the wall surrounding 90 the hole and facilitating the manipulation of bolts or nuts bearing thereon.

In order to get at the interior wall of the beam where these bolts enter, I provide suitable perforations in the horizontal walls 2 95 and 5. These perforations are indicated at 15 and 16 in the lower wall and at 17 and 18 in the intermediate wall. By means of these perforations all of the bolt heads or nuts located on the interior walls of the beam may be easily reached by a mechanic. Access through the top wall of the beam is not provided as it would be undesirable because of the fact that trainmen frequently stand on the beam and would be likely to 100 have their feet caught in openings there provided and as a result be liable to dangerous accidents.

By this construction the locomotive frame, 110 the end braces, the pilot, pilot braces, draw-

bar coupler, and other parts not shown on the drawings may be secured to the beam by comparatively short bolts which extend only through the adjacent beam wall. If 5 the nuts are placed on the inside of the beam they are substantially protected from the weather and may be removed more easily than if exposed and rusted or injured by blows.

10 Various modifications in the details of my beam may be made without departing from the spirit of my invention as expressed in the appended claims.

I claim:

15 1. In a pilot beam, front, rear, top and bottom walls and an intermediate horizontal member extending the entire length of the beam and perforated to provide access to connecting bolts terminating within the 20 beam.

25 2. In a pilot beam, front, rear, top and bottom walls and an intermediate horizontal member extending the entire length of the beam and perforated to provide access to connecting bolts terminating within the beam, the beam being open at both ends and having an unobstructed opening from end to end above the horizontal member.

30 3. In a pilot beam, front, rear, top and bottom walls and an intermediate horizontal member extending the entire length of the beam and perforated to provide access to connecting bolts terminating within the beam, the beam being open at both ends, and 35 having an unobstructed opening from end to end below the horizontal member.

40 4. In a pilot beam, front, rear, top and bottom walls, and an intermediate horizontal member extending the entire length of the beam and perforated to provide access to connecting bolts terminating within the beam, the beam being open at both ends and 45 having unobstructed openings from end to end above and below said horizontal member.

5. In a pilot beam, front, rear, top and bottom walls and an intermediate horizontal member extending the entire length of beam and perforated to provide access to connecting bolts terminating within the beam, the 50 bottom wall being depressed at its middle portion.

6. In a pilot beam, a top wall extending the full length of the beam, a bottom wall terminating short of the ends of the beam, 55 an intermediate member parallel with said top and bottom walls, extending the full length of the beam and provided with openings adjacent to the ends of said bottom wall to permit access to the interior, top, front and rear walls of the beam above said member and near the ends of said bottom wall.

7. In a one-piece pilot beam of rectangular cross section, a horizontal reinforcing wall intermediate the top and bottom walls of the beam, bolt holes in the top, bottom, front and rear walls of the beam, and openings in said intermediate wall to permit access from one side thereof to bolt holes on the 70 other side thereof.

8. In a one-piece pilot beam, vertical walls, horizontal walls, integral perforated bosses on the interior of said walls and 75 spaced from the ends thereof for bolts securing extraneous members, and openings in said horizontal walls adjacent to said bosses to permit access to the latter.

9. In a one-piece pilot beam, an upper portion comprising a box-like section extending 80 from end to end of the beam, and a lower wall below said section, connected thereto by integral front and rear walls, extending throughout a portion only of said section, and depressed in its middle part to form a 85 backing for a drawbar pocket.

In testimony whereof I hereunto affix my signature this 26th day of July, 1922.

CHARLES T. WESTLAKE.
